UNITED STATES PATENT OFFICE

WAYNE F. SHORT, OF BLOOMINGTON, INDIANA

COMBINATION BAR AND LEG COMPASS

Application filed December 29, 1926. Serial No. 157,821.

This invention relates to bar and leg compasses and one object is to combine the features of both in such a way that the resulting instrument will be more accurate and easy to operate than any previously known. Another object is to have one or both legs detachable from the bar so an extension can be used for large circles.

Referring to the accompanying drawings:

- 10 Fig. 1 is a side view of the whole instrument. Fig. 2 is a view of a pencil or needle point attachment for the instrument. Fig. 3 is a front end view of one slider. Fig. 4 is a view of a pen attachment.
- 15 Two sliders 15 carrying working instruments are mounted on the graduated bar 16 and are connected to the legs 5. They are slotted on one or both sides and carry a vernier scale having a zero point located above the 20 working points of the working instruments and readable on the graduated bar. On the lower edges of the sliders are projections 18 which serve to hold the pen, pencil or points in position. Set screws 19 screw against the 25 ends of the removable working instruments and make them secure. On the upper edges of the sliders are set screws 14 which serve to clamp the sliders to the bar after they are set at the desired position. Square vertical 30 projections 12 on the upper edges of the sliders with pins 13 hold the binding posts 11 in place.

These posts are slotted and fit into the 35 connectors 8 and around the screws 10 and are made secure by the thumb-nut 9 which draws the two sides of each connector together. These connectors have narrowed ends and pivot loosely on screws 7. Legs 5 are enlarged and flattened at their upper ends 40 and pivot loosely on screws 4 in the saddle-piece 3. Screw 6 is placed through the lower end of the saddle-piece and holds it in shape. Handle 1 screws into the saddle-piece.

The zero of the bar is in its center or inward from the ends.

For drawing large circles an extension to one or both legs can be inserted between the sliders and legs.

With this description of my invention what 50 I claim is:

1. In a compass the combination of a graduated bar, two sliders mounted on the bar and each being slotted on one of its sides longitudinally of the bar, one edge of each slot being provided with a vernier, a working instrument having a working point carried by each slider, each vernier having its zero point in a plane perpendicular to the bar and including the working point of the working instrument of the corresponding slider, 55 means for releasably holding the sliders in the positions to which they are adjusted, a handle member, and two legs each connected at one end to one of the sliders and pivotally connected to each other at their other ends and 60 to the handle member.

2. In a compass the combination of a graduated bar, two sliders mounted on the bar, binding posts carried by the sliders, working instruments carried by the sliders, means for clamping the sliders to the bar, two connectors each attached to one of the binding posts, two legs pivotally connected at one end to each other and to the two connectors at 70 their other ends, and means for clamping the 75 connectors to the binding posts.

In testimony whereof I affix my signature.

WAYNE F. SHORT.
